UNITED STATES PATENT OFFICE.

PORTER HOWELL REED, OF CAIRO, NEW YORK; ALICE A. REED EXECUTRIX
OF SAID PORTER HOWELL REED, DECEASED.

WEATHER-STRIP.

SPECIFICATION forming part of Letters Patent No. 451,641, dated May 5, 1891.

Application filed November 5, 1889. Serial No. 329,334. (No model.)

To all whom it may concern.

Be it known that I, PORTER HOWELL REED, a citizen of the United States of America, residing at Cairo, in the county of Greene and State 5 of New York; have invented certain new and useful Improvements in Weather-Strips for Doors, of which the following is a specification, reference being had therein to the accompanying drawings.

- 10 My invention relates to improvements in automatic weather-strips for the bottoms of doors; and the objects of my improvements are, first, to provide a weather-strip which is absolutely rain-proof and dust-proof; second, 15 to provide a weather-strip which will accommodate itself to any inequalities of surface on the door-sill; and, third, to provide a simple and inexpensive mechanism which is not liable to get out of order. I attain these objects by the use of the mechanism illustrated 20 in the accompanying drawings, in which—

Figure 1 is a sectional elevation of a door with my improvements applied. Fig. 2 is a side sectional elevation of a door about to be 25 closed; and Fig. 3 the same as last, with door closed, containing my improvements. Fig. 4 is a side elevation, bottom up, in detail, of my improvements and showing the under side.

- 30 3 represents a metallic rod forming one side of a metallic frame, as shown in Fig. 4. It extends across the side of the door at the bottom, and is attached thereto by the eyes 8 8, in which it turns, its end being bent to form the curved arm 4, said curved arm being 35 placed toward the free edge of the door. The corresponding side 6 of said metallic frame is formed from a single metallic rod or wire of a smaller diameter than the rod 3, said wire being bent at its ends at right angles 40 and the ends extended so as to be connected with and be securely fastened into the side of and near the ends of the rod 3, thus forming the remaining side and the ends of said metallic frame, which extends across the bottom 45 of the door and being adapted to carry the flexible covering 2. Said metallic frame is flexible, and the side 6 is adapted to accommodate itself to the inequalities of the door-sill when applied to a door where the sill 50 has been worn away and become uneven.

The curved arm 4 is adapted to engage the door-frame at the point of contact 5 in closing the door, by means of which the free side 6 of said metallic frame is powerfully forced by the weight of the door down upon the door-sill and made to conform to any inequalities in the sill, the frame thus carrying the flexible covering and making the weather-strip both dust-proof and rain-proof. 55

7 represents a small spiral spring, which is 60 attached to the metallic rod 3, and is adapted to raise the free side of the metallic frame and its flexible covering when the door is opened.

2 represents a longitudinal flexible covering, one edge being securely fastened to the side of the door above the rod 3 by the fillet or band, the opposite edge being fastened in a suitable manner to the free side 6 of said metallic frame, as shown at 10, Fig. 4. Said 70 flexible covering may be of any suitable material. I prefer rubber.

5 represents the point of contact of curved arm 4 with the door-frame.

9 represents the door-sill.

11 represents a fillet or band by means of which the edge of the flexible covering 2 is fastened to door. 75

The operation of the foregoing-described mechanism is extremely simple. Its adaptability to the purposes designed is obvious without further explanation. The several parts having been duly adjusted as described and set forth, on closing the door the curved arm 4 engages at point of contact 5 the side 80 of the door-frame, by which means the free side 6 of the flexible metallic frame and the flexible covering 2 are forced down upon the door-sill 9, accommodating themselves to any inequalities in the door-sill, as set forth. 90

Having fully described my invention, what I claim as new, and desire to secure by Letters Patent in an automatic weather-strip, is—

1. The combination of an elongated flexible metallic frame adapted to be attached to the bottom of the side of a door and to carry a flexible covering, the rod forming the side of the frame which is attached to the door being extended toward the free edge of the door and bent downward, forming a curved arm, 100

one edge of said covering being fastened also to the bottom of the side of the door, the other edge being fastened to the free side of said frame, and of the spiral spring 7, as and for the purposes set forth and described.

2. An automatic weather-strip for the bottoms of doors, consisting of a longitudinal flexible metallic frame adapted to be attached to the bottom of the side of a door by means of the eyes 8 8, the end of the rod forming the side of the frame which is attached to the door being extended toward the free edge of the door, forming a curved arm, said frame being also adapted to carry a flexible covering, one edge of said covering being attached by a fillet or band 11 to the side of the door above the eyes 8 8, the other edge being secured to the free side 6 of said frame, and of the spiral spring 7, all in combination, as and for the purposes substantially as described.

3. An automatic weather-strip consisting, essentially, of an elongated flexible metallic frame carrying a flexible covering and adapted to be attached to the bottom of the side of a door by suitable means, the rod 3 (forming 25 one side of said frame) being extended at the end toward the free edge of the door to form a curved arm 4 of the spiral spring 7, and the fillet or band 11, all in combination, as and for the purposes substantially as set forth 30 and described.

In testimony whereof I affix my signature in presence of two witnesses.

PORTR. HOWELL REED.
